UNITED STATES PATENT OFFICE.

LOUIS PROPP, OF NEW YORK, N. Y.

SWITCH-CONTROLLED ELECTRICAL CONNECTER PLUG.

Application filed June 3, 1927. Serial No. 196,235.

This invention relates to switch-controlled electrical connecter plugs.

An object of the invention is to provide a unit cheaply manufactured and easily assembled accomplished by the simplification of the constituent parts and the reduction of the number of these parts.

A further object of the invention is to provide a simple electric switch within the ordinary plug connecter as now generally in use for completing the necessary electric circuits in operating electric irons, percolators, etc.

A further object is the introduction of a novel switch into apparatus of this type to eliminate the necessarily intricate parts of the ordinary snap action switch, provision being made for actuating such a switch into either on or off position by the same finger.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is an elevation of a connecter plug embodying the invention, a portion of the side wall being broken away to disclose the switch, its actuating means and the connections thereto;

Fig. 2 is an elevational view of the inner face of one of the plates comprising the plug, all the metal parts being removed;

Fig. 3 is a like elevational view of the inner face of the associated plate;

Figs. 4, 5 and 6 are front, side and rear elevational views, respectively, of one of the switch elements;

Fig. 7 is a isometric view of the finger-actuated lever for the switch;

Figs. 8, 9 and 10 are rear, side and front views, respectively, of another single element of the switch; and

Fig. 11 is a sectional view on line 11—11 of Fig. 1 of the casing member alone.

Referring in detail to the drawing, 2 denotes the casing of a connecter plug of the usual two-part construction comprising two complementary members 2^a ordinarily made from phenol condensation products or other non-conducting material, easily worked in a mold. The usual enlargements 2^c are provided for gripping the casing in making and breaking a connection. The members 2^a are formed with grooves 3, 4, 5 and 6 which, when the members are placed with their inner faces in juxtaposition, form passages 2^a into which the terminal prongs ordinarily provided upon the electrical appliances (not shown), may be inserted to make contact with the current carrying parts within said passages 2^a hereinafter described.

Extending through the members 2^a are openings 7, 8, 9 and 10 for the reception of the customary retaining means such as the screws and nuts 11 for securing the members in face to face contact, see Fig. 1.

The current carrying parts above referred to include a spring member 14 receiving and retaining its associated spring member 15 in such manner as to make a positive metal contact with a terminal prong inserted between them.

Located within one of the enlargements 2^c is resilient blade 16, one of the elements of the switch provided for controlling the operation of the appliance to which the plug is attached. This blade, the construction of which is clearly shown by Figs. 4 to 6, is made of spring metal preferably stamped to provide an ear 17 having an opening 18. This ear together with extensions provided upon the spring members 14 and 15 are clamped together by a screw 18^a threaded into the member 14 thereby making the necessary metallic contact between these parts. Bent at right angles to and extending outwardly from ear 17 and upwardly therefrom is an arm 19 which is then turned backward upon itself to provide a portion 20 which, as shown in Fig. 6, is preferably made broad and flat for purposes hereinafter appearing.

Located in proximity to this downturned portion 20 is the contact lug 21 of the switch element 22. This element is preferably made of a metal stamp having a bearing por-

tion 23 formed by bending the metal at right angles to lug 21, said portion 23 being adapted to conform to the retaining depression 24 formed in one member 2^b, so that when assembled, the possibility of element 22 moving out of place is avoided. Further provision for rigidity of element 22 is provided by the depression 2^a in member 2^b into which extension 21^a on lug 21 extends when the 10 plug is assembled. The coaction of extension 21^a with depression 2^a together with the retention of the entire lug 21 by the flat sides of raised surfaces 2^e retains the element 22 and prevents any movement thereof. Portion 15 23 is provided with openings at 25 and 26. Opening 25 is threaded for the reception of screw 29 to attach one of the electrical conductors (not shown) to element 22. The other opening 26 provides a journal for the 20 reception of one pivotal end 27^a of shaft 27 which extends through the finger actuated lever 28. This lever may be made of the same material as the casing 2 or of other insulating material so as to be non-conducting 25 at the point of operation by the user's finger. The other pivotal end 27^b of said shaft is received in opening 30 provided in the other member 2^b. Said lever has an arm 31 extending without the plug through an opening 30 formed by the association of recesses 32 and 33 in members 2^b. The end of the handle opposite arm 31 is formed with a presser end 34 which upon actuation of the lever 28 may be made to press the downturned spring 35 portion 20 so as to bring the blade 16 into engagement with the lug 21 to complete the electrical connection. The spring portion 20 is so formed as to force the presser end 34 in an upward direction and so retain it in 40 actuated position.

By moving the lever to the position shown in dotted lines in Fig. 1, the portion 20 is allowed to move away from lug 21 to break the circuit. Effective quick make and break is obtained by rounding off the presser end 34 in the manner shown at surface 37. Before the resilient blade 16 will have released from contact with lug 21, the rounded surface 37 will be in contact with the downturned portion 20, and the force exerted by blade 16 will be far enough beyond the effective center of the lever 28 to allow the blade 16 to snap quickly away from the lug 21, carrying the lever 28 with it.

In the passage formed by grooves 3 and 5 are placed current carrying parts 35 similar to members 14 and 15. In the end of the plug opposite to said passage another passage 36 is provided through which the ends 60 of a flexible cable is inserted, one wire of which is connected to screw 29 in the manner previously described while the other wire is directly connected to the current carrying parts 35 in the well understood manner. An

annular groove 36^a may be provided communicating with the passage 36 for anchoring a coiled strain relief member (not shown).

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. An electrical connector plug having switch means therein, said plug having an opening in one corner thereof, an actuating lever for said switch extending through said opening, one pole of said switch being a spring member having a down-turned portion, the second pole of said switch comprising a plate formed with an out-turned lug located adjacent the said spring member, said lever having a presser member to engage said down-turned portion whereby said lever, upon actuation, presses said spring member against said lug.

2. An electrical connector plug having switch means therein, there being an opening in one corner of said plug, an actuating lever for said switch extending through said opening, one pole of said switch being a spring member having a down-turned portion, the second pole of said switch comprising an element formed with an out-turned lug, located adjacent the said spring member, said lever having a presser member to engage said down-turned portion, whereby actuation of said lever presses said spring member against said lug, said element being formed with pivot means for said lever.

3. An electric connector plug comprising a sectional casing having current carrying parts therein, a switch included in said parts comprising a resilient blade secured to one of said current carrying parts, said blade being formed with a downwardly turned portion, a lever having a presser end for contacting with said portion, a switch element formed with journal means for said lever, said element having a lug located adjacent the resilient blade, whereby said lever, when moved in one direction into contact with said downturned portion, moves the blade into contact with said lug.

4. An electric connector plug comprising a sectional casing having current carrying parts therein, a switch included in said parts comprising a resilient blade secured to one of said current carrying parts, said blade

having a downwardly turned portion, a lever having a presser end for contacting with said portion, a switch element formed with journal element means for said lever, said element 5 having a lug located adjacent the resilient blade, whereby said lever, when moved in one direction into contact with said downturned

portion, moves the blade into contact with said lug, said presser end having means to allow quick release thereof upon movement 10 of the lever in the opposite direction.

In testimony whereof I affix my signature.

LOUIS PROPP.
